United States Patent Office

Des. 223,206

Patented Mar. 28, 1972

223,206

DRESSER OR THE LIKE

Joseph E. Adkinson, 3807 Leland St.,
Chevy Chase, Md. 20015

Filed Apr. 20, 1970, Ser. No. 22,526

Term of patent 7 years

Int. Cl. D6—04

U.S. Cl. D33—6

The figure is a view in perspective of the dresser of the present invention.

The side of the article not shown is a mirror image of the side shown while the back is plain and unornamented.

I claim:

The ornamental design for a dresser or the like, substantially as shown and described.
